UNITED STATES PATENT OFFICE.

CHARLES THOMAS, OF VICTORIA, BRITISH COLUMBIA, CANADA.

INTERNAL-COMBUSTION ENGINE.

Specification of Letters Patent.

Patented Aug. 19, 1919.

1,313,762.

Application filed January 28, 1919. Serial No. 273,678.

To all whom it may concern:

Be it known that I, CHARLES THOMAS, a subject of the King of Great Britain, residing at Victoria, in the Province of British Columbia and Dominion of Canada, have invented new and useful Improvements in Internal-Combustion Engines, of which the following is a specification.

This invention relates to improvements in internal combustion engines and has particular application to means for feeding air to the engine cylinders and for cutting off the flow of gas to said cylinders when the motor vehicle in which the engine is installed is descending a grade.

In carrying out the present invention it is my purpose to provide means whereby when a motor vehicle is descending a grade, the flow of gas in the engine cylinders may be cut off and the cylinders placed in communication with the atmosphere so that air may be delivered to said cylinders in place of the usual explosive mixture, thereby cooling the engine cylinders and at the same time enabling the pistons in the cylinders to act as brakes to check the speed of the car vehicle down the incline.

It is also my purpose to provide a means of the class described which will embrace the desired features of simplicity, efficiency and durability, which may be manufactured and installed at a small cost, and which will operate efficiently and effectively under all conditions.

With the above recited objects in view and others of a similar nature, the invention resides in the construction, combination, and arrangement of parts set forth in and falling within the scope of the appended claim.

In the accompanying drawings:

The figure is an enlarged fragmentary side elevation with a motor vehicle internal combustion engine equipped with means constructed in accordance with my invention, the intake manifold being shown partly in section and partly in elevation.

Referring now to the drawing in detail, 1 designates the intake manifold of the internal combustion engine while 2 indicates the 50 intake pipe leading from the carburetor or

other vaporizing device to the manifold 1 so that the gaseous mixture may be delivered to the manifold and from the manifold to the cylinders of the engine.

Arranged across the intake pipe 2 is a 55 butterfly valve 4 and connected with the intake pipe 2 in advance of the butterfly valve 4 is a branch pipe 5 in open communication with the intake pipe 2. Arranged across the branch pipe 5 is a butterfly valve 6 arranged 60 at right angles to the butterfly valve 4 in the intake pipe. Connecting the butterfly valves 4 and 6 for simultaneous movement is a shaft 7 that is provided with an arm 8 arranged at right angles to the shaft and connected with one end of the control rod 9. The other end of the control rod 9 is connected with an operating lever that is arranged within convenient reach of the driver or operator of the motor vehicle.

In the present instance the butterfly valves 4 and 6 have their axes and pivot points disposed in alinement with each other so that both valves may be operated from the shaft 7 simultaneously without the need of 75 employing any mechanism between the shaft 7 and the valve.

In practice, the valve 4 is normally opened and the valve 6 normally closed, so that the gaseous mixture in the carburetor may be 80 delivered to the engine cylinders as usual, but when the car is descending a grade, the control rod 8 is operated and it rotates the shaft 7 so as to close the valve 4 and open the valve 6, thereby cutting off communication 85 between the engine cylinders and the carburetors and establishing communication between the engine cylinders and the atmosphere by way of the intake pipe and advance pipe 5. When this condition prevails, air flows into the cylinder to cushion the movement of the piston so that the engine may be utilized as a brake to check the speed of the vehicle down the incline. This air also acts as a cooling agent to lower the 90 temperature of the cylinders.

I claim:—

The combination with the intake pipe of an internal combustion engine, and a branch pipe communicating with the intake pipe 100

and opening into the atmosphere, of a duplex valve including a stem, and a valve disk on each end of the stem, said disks being arranged within said pipe and disposed in 5 right angular relation, whereby when one of said valves is closed the other is opened, an eye projecting horizontally from said stem

and arranged between said pipes and a manually operable rod having a hooked extremity engaged in said eye to rotate said 10 stem and simultaneously operate said valves.

In testimony whereof I affix my signature.

CHARLES THOMAS.
